United States Patent Office.

DANIEL LIEBRICH, OF PHILADELPHIA, PENNSYLVANIA.

Letters Patent No. 71,627, dated December 3, 1867.

IMPROVED DOOR-GONG.

The Schedule referred to in these Letters Patent and making part of the same.

TO ALL WHOM IT MAY CONCERN:

Be it known that I, DANIEL LIEBRICH, of the city and county of Philadelphia, and State of Pennsylvania, have invented a new and improved Alarm-Gong; and I do hereby declare that the following is a full, clear, and exact description of the same, reference being had to the accompanying drawing, and to the letters of reference marked thereon.

My invention consists of an alarm-gong, the hammer of which is on and strikes the bell from the outside. The hammer and the trip-lever are attached to each other, the latter vibrating on a stud of the former. The loose end of a spiral spring takes against a pin in the upper end of the trip-lever, and causes the hammer, when drawn back and then suddenly released, to spring and strike the bell. The hammer has a projection, which takes against the bottom plate of the hammer and spring-plate, which serves for a spring, whereby it is suddenly withdrawn after striking the bell; and of such other mechanism as is hereinafter shown and described. On reference to the accompanying drawing—

Figure 1 is a front view of my new and improved alarm-gong, and

Figure 2 is a side view of the same.

Similar letters refer to similar parts in the two views.

A is a bell, suspended from the back plate B of an alarm-gong by the stud a. C is an angular plate, fixed to the outer surface of the bell by the stud a, and the nut b. c is a stud, fixed to the side of the angular plate C; it extends horizontally across the bell. D is a curved arm or hammer, on the outer end of the said stud c, reaching to the bottom of the bell. d is a projection or striker on the upper edge, at its lower end, nearly touching the bell. E is a trip-lever, vibrating on the pin e of the extension of the hammer, their surfaces being in contact. F is a spiral spring on the stud c. One end of it is looped to take over the pin f projecting from the side of the plate C; the other end extends downwardly and takes against the pin g of the trip-lever E. One end of said pin bears against the under side of the lower end of the hammer D, to prevent the lever E from rotating on the pin e, when pressure is applied to its lower end, tending to press it outwardly. h is a projection of the hammer E; it bears against the back of the angular plate C. H is trigger, which is fixed to the door over which the gong is placed; its upper end projects a slight distance behind the trip-lever E. The accompanying drawing shows the trigger H in position behind the lever E. On opening the door, it vibrates the lever E in that direction, also the hammer D, they being connected by the pin e, until the door is opened sufficiently to trip the lever E. The spiral spring F, by its end k bearing against the pin g of the lever E, throws the hammer D and lever suddenly back. The projection d, striking the bell, causes it to ring. The projection h of the hammer taking against the back of the angular plate, which acts by springing the hammer from the bell, thereby preventing it from deadening its sound.

When it is desirable to throw the gong out of use, lift the end of the spiral spring F into the groove m, formed in the edge of the trip-lever E, which throws back the end of the trip-lever, (shown in red lines, fig. 2,) so as not to be acted on by the trigger H when opening the door.

What I claim as my invention, and desire to secure by Letters Patent, is—

1. The angular plate C, hammer D, trip-lever E, spiral spring F, and the stud c, when combined and arranged as shown and described.

2. The hammer D, trip-lever E, and the pin g, as shown and described.

3. The hammer D, trip-lever E, pin g, and the spiral spring F, as shown and described.

In testimony whereof, I hereunto sign my name to this specification in presence of two subscribing witnesses.

DANIEL LIEBRICH.
